(57) **CLAIM**

The ornamental design for a square artist brush, as shown
and described.

DESCRIPTION

FIG. 1 is a top perspective view of a square artist brush,
showing my new design;

FIG. 2 is a bottom perspective view thereof;

FIG. 3 is a front elevation view thereof, the rear elevation
view being a mirror image thereof;

FIG. 4 is a top plan view thereof;

FIG. 5 is a bottom plan view thereof;

FIG. 6 is a right side elevation view thereof; and,

FIG. 7 is a left side elevation view thereof.
